UNITED STATES PATENT OFFICE

2,546,765

INVALID'S BEDCHAIR

Tress L. McKinley, Temple, Tex.

Application October 1, 1948, Serial No. 52,327

8 Claims. (Cl. 155—28)

1

The present invention relates to invalid's bed chair and it consists in the combinations, constructions and arrangements of parts herein described and claimed.

It is an object of the present invention to provide a device of the character set forth having means whereby the same may be propelled manually in the manner of a conventional invalid's chair.

Another object of the invention is the provision, in a device of the character set forth, of hydraulic means for raising the invalid supporting portion of the device with respect to the chassis thereof.

Another object of the invention is the provision of means whereby the invalid supporting portion of the device may be placed in a rigid reclining position at selected heights with respect to the chassis.

Another object of the invention is the provision of novel means, in a device of the character set forth, for the mounting of an axle forming a part of the invention.

Other and further objects of the invention will become apparent from a reading of the following specification taken in conjunction with the drawings, in which:

Figure 1 is a side elevational view of an embodiment of the invention.

Figure 2 is a view similar to Figure 1 but showing a portion of the device in elevated position.

Figure 3 is a fragmentary rear elevational view of the device shown in Figures 1 and 2.

Figure 4 is a fragmentary front elevational view thereof.

Figure 5 is a fragmentary side elevational view of a portion of the device.

Figure 6 is a plan view of Figure 5.

Figure 7 is a fragmentary side elevational view of the device in another position it may assume, and

Figure 8 is a fragmentary perspective view illustrating certain details of the invention.

Generally there is provided an invalid's bed-chair which is provided with a chassis having a vertically adjustable axle for a pair of relatively large wheels and having a pair of swivelly mounted wheels for further support. A seat is supported upon an hydraulic jack which is, in turn, operable by means of a foot lever and controllable by a hand-operated valve. The seat is provided with a pivotally mounted back having means for locking the same in selected positions and which is connected by arm rests with a foot-rest frame. Individual foot rests are so mounted as to be independently adjustable forwardly and

2

angularly with relation to the seat and foot-rest frame.

Referring more particularly to the drawings, there is shown therein an invalid's bed-chair having a chassis 10 having a pair of supporting casters 11 at the rear thereof and having an axle 12 selectively and adjustably mounted in a series of openings 13 provided in either side of the forward end of the chassis.

10. In a dependant portion 14 of the chassis substantially centrally disposed thereon is affixed a base 15 of a vertically extending piston 16.

Vertically slidably but non-revolubly mounted upon the piston 16 is a sleeve 17 affixed to a collar 18 attached to the central portion of the bottom of a seat frame 19.

A hydraulic pump 20 is mounted on the dependant portion 14 for raising and lowering the sleeve 17 with respect to the piston 16 in conventional manner and a lever 21 is provided for the pump 20 and extending rearwardly and terminates in a foot pedal 22. A spring 23 interconnects the upper end of the chassis and the lever 21.

25. The seat frame 19 is provided with a fixed seat 24 and to ears 25 on the seat frame 19 is pivoted a back member 26 having an arcuate slotted brace 27 upon either side thereof. Bolts 28 upon either side of the seat frame 19 extend through the braces 27 which may be adjustably locked thereon by means of wingnuts 29.

A U-shaped leg support frame 30 rests against the forward end of the seat frame 19 and is pivotally connected at its upper ends to the forward ends of arm rests 31, the rear ends of which are pivotally connected to the back member 26.

At either side of the seat frame 19 is affixed a tube 32 in each of which is slidably mounted a rod 33 the outer ends of which are provided 35 with eyes 34 through which extends a transverse shaft 35. Upon the shaft 35 is revolvably mounted a pair of U-shaped leg supports 36 each having a foot rest 37.

The outer arms of each of the members 36 is provided with a U-shaped bracket 38, the inner arm 39 of each of which is affixed to the shaft and the outer arm 40 of each of which is free to move. The shaft 35 extends through both arms 39 and 40 and a wingnut 41 is threadably mounted at either end of the shaft.

Various sized wheels 42 may be mounted upon the axle 12 and a valve operating handle 43 extends upwardly and rearwardly from the pump 20 from a release valve in said pump.

In operation, it will be apparent that the back

member may be affixed in any desired position from a horizontal one to a vertical one by means of the braces 27 and wingnuts 29, and that movement of the back will cause a corresponding movement of the frame 30 through its connection with the arm rests 31. It will also be seen that the leg supports 36 may be moved forwardly and rearwardly by means of moving the rods 33 through the tubes 32 and locked in selected positions by thumbscrews 44 mounted in the tubes. The leg supports may be selectively positioned angularly, also, by revolving the brackets 38 upon the shaft 35 and then tightening the wingnuts 41 against the arms 40 to frictionally encompass the eyes 34 between the arms 39 and 40.

To raise the seat and its attendant mechanisms, it is only necessary to operate the pump 20 by pressing down upon the pedal 22, the spring 23 acting to return the lever 21 and its pedal 22 to its normal upward position. To lower the chair, the valve handle 43 is manipulated to release the pressure within the sleeve 17.

While but one form of the invention has been shown and described herein, it will be readily apparent to those skilled in the art that many minor modifications may be made without departing from the spirit of the invention or the scope of the appended claims.

What is claimed is:

1. A device of the character described comprising a wheeled chassis, a seat, a hydraulic jack mounted upon the chassis and supporting the seat, an adjustable back hinged to the seat, a leg supporting frame, arm rests interconnecting the leg supporting frame and the back and independently adjustable foot rest members supported by the seat.

2. A device of the character described comprising a wheeled chassis, a seat, a hydraulic jack mounted upon the chassis and supporting the seat, an adjustable back hinged to the seat, a leg supporting frame, arm rests interconnecting the leg supporting frame and the back, independently adjustable foot rest members supported by the seat, a pump for the jack and a foot lever for operating the pump.

3. A device of the character described comprising a wheeled chassis, a seat, a hydraulic jack mounted upon the chassis and supporting the seat, an adjustable back hinged to the seat, a leg supporting frame, arm rests interconnecting the leg supporting frame and the back, independently adjustable foot rest members supported by the seat, a pump for the jack, a foot lever for operating the pump and a spring for returning the lever to normal upward position.

4. A device of the character described comprising a wheeled chassis, a seat, a hydraulic jack mounted upon the chassis and supporting the seat, an adjustable back hinged to the seat, a leg supporting frame, arm rests interconnecting the leg supporting frame and the back, independently adjustable foot rest members supported by the seat, a pump for the jack, a foot lever for operating the pump, a spring for returning the

lever to normal upward position, a valve for the pump and an elongated upwardly extending handle for operating the valve.

5. A device of the character described comprising a chassis having a pair of casters at the rear thereof and a vertically adjustable axle at the front thereof, wheels mounted upon said axle, a hydraulic jack mounted upon the chassis, a seat mounted upon the jack, an adjustable back hinged to the rear of the seat, a leg supporting frame at the front of the seat, arm rests interconnecting the frame and the back and foot rests having means for angular and horizontal adjustment with respect to the seat.

15 6. A device of the character described comprising a chassis having a pair of casters at the rear thereof and a vertically adjustable axle at the front end thereof, wheels mounted upon said axle, a hydraulic jack mounted upon the chassis, a seat mounted upon the jack, an adjustable back hinged to the rear of the seat, a leg supporting frame at the front of the seat, arm rests interconnecting the frame and the back, foot rests having means for angular and horizontal adjustment with respect to the seat, a pump for the jack and a foot lever for operating the pump.

20 7. A device of the character described comprising a chassis having a pair of casters at the rear thereof and a vertically adjustable axle at the front thereof, wheels mounted upon said axle, a hydraulic jack mounted upon the chassis, a seat mounted upon the jack, an adjustable back hinged to the rear of the seat, a leg supporting frame at the front of the seat, arm rests interconnecting the frame and the back, foot rests having means for angular and horizontal adjustment with respect to the seat, a pump for the jack and a foot lever for operating the pump.

25 30 8. A device of the character described comprising a chassis having a pair of casters at the rear thereof and a vertically adjustable axle at the front thereof, wheels mounted upon said axle, a hydraulic jack mounted upon the chassis, a seat mounted upon the jack, an adjustable back hinged to the rear of the seat, a leg supporting frame at the front of the seat, arm rests interconnecting the frame and the back, foot rests having means for angular and horizontal adjustment with respect to the seat, a pump for the jack, a foot lever for operating the pump, a spring for returning the lever to normal upward position, a valve for the pump and an elongated upwardly extending handle for operating the valve.
